Geneva Clay*

UNITED STATES PATENT OFFICE.

GENEVA CLAY, OF DOYLESTOWN, PENNSYLVANIA.

DESIGN FOR A PIN, BADGE, CHARM, OR ARTICLE OF SIMILAR NATURE.

53,290.

Specification for Design.

Patented May 13, 1919.

Application filed March 8, 1919. Serial No. 281,556. Term of patent 3½ years.

To all whom it may concern:

Be it known that I, GENEVA CLAY, a citizen of the United States, residing at Doylestown, in the county of Bucks and State of Pennsylvania, have invented a new, original, and ornamental Design for Pins, Badges, Charms, or Articles of Similar Nature, of which the following is a specification, refer-

ence being had to the accompanying drawing, forming part thereof.

Poppies growing between crosses, with birds in sky, and title "Flanders fields".

I claim:

The ornamental design for a pin, badge, charm, or article of similar nature, as shown.

GENEVA CLAY.
